ROTARY SWAGING MACHINE

Frank Patnaude, Warwick, R. I., assignor, by
mesne assignments, to Cread Engineering and
Research Company, Cranston, R. I., a corpora-
tion of Rhode Island

Application April 17, 1943, Serial No. 483,418

3 Claims. (Cl. 78—20)

1

The present invention relates to rotary swaging machines of the type comprising cooperating dies which are continuously rotated around the work and reciprocated radially during their rotation to progressively swage the periphery of the work.

One of the objects of the present invention is to provide a machine of the type indicated for applying annular fittings of various shapes to articles of manufacture.

Another object is to provide a machine of the type indicated in which the dies are reciprocated continuously through a constant stroke and progressively advanced radially inwardly toward each other during a swaging operation.

Another object is to provide a machine of the type indicated in which the dies may be opened radially to receive the work therebetween and progressively closed together during a swaging operation.

Another object is to provide a machine of the type indicated in which the reciprocating dies are positively advanced with a predetermined controlled rate of motion to cause the work to be compressed gradually.

Another object is to provide a machine of the type indicated with manually-controlled hydraulically-operated means for progressively closing the dies.

Further objects of the invention are set forth in the following specification which describes a preferred construction of machine embodying the invention and several kinds of fittings adapted to be swaged by the machine, by way of example, as illustrated by the accompanying drawings.

In the drawings:

Fig. 1 is a longitudinal sectional view of a rotary swaging head incorporating the novel features of the present invention and showing the dies as in their open position;

Fig. 2 is a transverse sectional view on line 2—2 of Fig. 1 showing the means by which the dies are rotated and reciprocated simultaneously;

Fig. 3 is a detailed view of the forward end of the swaging head similar to that illustrated in Fig. 1 and showing the operating wedges as advanced to close the dies;

Fig. 4 is a sectional plan view on line 4—4 of Fig. 1 showing the operating means for the wedges and the interlocking tongue-and-groove connection of the wedges therewith;

Fig. 5 is a detailed sectional view of the work-holding guide showing the separable parts of the guide as in spaced relationship to permit the work to be entered therebetween;

Fig. 6 is a diagrammatic view of the hydraulic

2

circuit and motor for operating the wedges to open or close the dies;

Fig. 7 is a longitudinal sectional view through the swaging head showing a modified form of construction of the dies for applying a cylindrical bearing sleeve to an article; and

Fig. 8 is a similar view showing the dies as closed against the work at the completion of a swaging operation.

With the usual types of rotary swaging machines the dies are simultaneously rotated and reciprocated through a constant stroke and are provided with cooperating tapered recesses forming an axial opening therebetween. The work to be swaged is moved axially through the opening between the dies and the latter operate to progressively swage and reduce the work as it advances between the tapered recesses. The swaging operation in such a machine forms the work with a cylindrical periphery.

In accordance with the present invention the dies are reciprocated through a constant stroke during their rotation about the work, being first opened to receive the work and then progressively advanced radially inwardly toward each other to compress the work. The dies are positively actuated with a predetermined controlled rate of movement so that the work positioned between the dies is gradually compressed radially without any axial movement thereof. The swaging machine of the present invention is particularly adapted for applying annular fittings to various types of articles, for example, spherical or cylindrical fittings to cables, rods, shafts and the like.

In the embodiment of the invention illustrated in Figs. 1 to 6 of the present drawings the machine is adapted to apply spherical fittings or abutments W to the end of flexible motion-transmitting cables C such as used in the controls of airplanes, motor-vehicles and the like.

Referring to Figs. 1 to 6 of the drawings, the rotary swaging machine of the present invention comprises spaced bearing housings 2 and 3 supported on a pedestal 4, only the upper portion of which is shown in Fig. 1. The spaced bearing housings 2 and 3 have aligned horizontal bores 5 and 6 through which a tubular drive-shaft or spindle 7 extends. The spindle 7 is journaled in ball-bearings 8 and 9 mounted in the housing 2 and ball-bearings 10 and 11 in the housing 3. Roller thrust-bearings 12 and 13 also are provided in the housing 2 and 3 to restrain the spindle against axial movement. The thrust-bearing 13 is mounted between an annular shoulder 14 in the housing 3 and an annular

shoulder 15 on a sleeve 16 shrunk onto, or otherwise secured to the enlarged end of the spindle 7. The thrust-bearing 12 is mounted between an annular shoulder 19 in the housing 2 and a collar 20 on the spindle 7. The thrust-bearings 12 and 13 are clamped between their seats 14, 15 and 19, 20 by a nut 21 screwed onto the threaded end 22 of the spindle 7 and set up tightly against the side of the collar 20, the nut being held against release by a check-nut 23 and a lock-washer 24.

The drive-shaft or spindle 7 has an enlarged end-portion 26 with a diametrical slot 27 extending across its forward face, see Figs. 1, 2 and 4. Slidably mounted in suitable bearing guides at the sides of the slot 27 is a pair of opposed hammers 28 and 29 having their radially outward faces 30 and 31 of arcuate contour. Between the hammers 28 and 29 is a pair of dies 32 and 33, later to be described in detail. Surrounding the enlarged end-portion 26 of the spindle 7 is an annular cage 34 supporting rollers 35 held in circumferentially-spaced pockets therein. Abutting the ends of the rollers 35 are retaining rings 36 and 37 and surrounding the cage 34 is a head-ring 38. Adjacent the retaining rings 36 and 37 are thrust-rings 39 and 40. The hammers 28 and 29 are guided at their forward sides by a ring 41 and at the rear by a plate 42, see Fig. 4. The ring 41 is mounted on the forward face of the end-portion 26 of the spindle 7 and overlies the forward sides of the hammers 28 and 29 and the plate 42 is mounted in grooves 43 in the end-portion 26 at the sides of the slot 27. At the front of the swaging head is a door 45 having an annular concaved guiding surface 46 with a tapped hole at its center in which a bushing 47 is screwed.

Mounted fast on a conical seat 48 on the spindle 7 between the bearing housings 2 and 3 is a flywheel 49. The flywheel 49 is connected to the spindle 7 for rotation therewith by a key 50 and is held against axial movement on its conical seat 48 by means of a nut 51 and check-nut 52 with a lock-washer therebetween. The flywheel 49 may be driven from a motor, not herein shown, by belts 53. As thus far described the machine is substantially identical with previously-used constructions.

In the embodiment of the invention illustrated in Figs. 1 to 6 of the present drawings each die 32 and 33 has a substantially semi-spherical recess 54 in its working face and a tapered guiding recess 55 in its forward face leading into the semi-spherical recess, see Fig. 3. At the rear of the recess 54 the die 33 is provided with a pair of tongues 56 which cooperate with correspondingly-shaped grooves 57 in the die 32. As shown in Fig. 1, the dies 32 and 33 also have a second set of cooperating spherical recesses 54 and guiding recesses 55 adjacent the rearward tongue 56 and groove 57. Due to this form of construction the dies may be reversed in position when one set of recesses becomes worn; or, if desired, the two sets of recesses may be made of different dimensions or shapes to adapt them to swage different types of work. As illustrated in Figs. 1 to 5 the dies 32 and 33 are particularly designed for swaging spherical fittings W onto the end of flexible cables C and the tongue 56 is adapted to be engaged by the end of the cable to position the fitting in alignment with the cooperating recesses 54 in the dies which confine and compress the material of the fitting as it is swaged in place.

Preferably, a work-holding guide 60 is provided for holding the cable C centrally of the dies 32 and 33 while the fitting W is being swaged in place 75

thereon. The workholder 60 is of tubular form to adapt it to fit closely within the bore of the bushing 47 in the door 45, its end 61 being tapered to conform to the cooperating tapered recesses 55 at the forward end of the dies 32 and 33 closely adjacent the semi-spherical recesses 54. Intermediate its ends the work-holding guide 60 is provided with a radial flange 62 for engagement with the face 63 of the bushing 47 in the door 45 to limit its inward movement between the dies 32 and 33. The work-holding guide 60 is provided with an axial bore 64 of the appropriate size to adapt it to receive and hold the cable C. Although the work-holding guide 60 may be made in one piece to adapt the cable C to be inserted through its axial bore 64, preferably, it is made in separable halves as shown in Fig. 5 to adapt it to be opened to receive the cable. In some instances, it may be desirable to hingedly connect the separable halves of the work-holding guide 60 at one side thereof to facilitate opening and closing the same.

In accordance with the present invention the dies 32 and 33 are arranged to be advanced inwardly toward each other during their reciprocation to swage the work W by progressively compressing and reducing it radially. For this purpose longitudinally-movable wedges 68 and 69 are provided between the hammers 28 and 29 and the dies 32 and 33. The wedges 68 and 69 are of a width to adapt them to slide in the slot 27 in the enlarged end-portion 26 of the spindle 7 at the rear of the plate 42, see Figs. 1 and 4. Each wedge has a horizontal face 70 for cooperation with the radially outward face of the die 32 or 33 and an inclined face 71 for cooperation with a correspondingly-inclined inward face 72 of the hammer 28 or 29. The wedges 68 and 69 extend through slots 73 in the plate 42 with their rearward ends positioned in a transverse slot 74 in the forward face of a horizontal operating member 75 extending axially of the spindle 7. As shown in Fig. 4, the operating member 75 has inwardly-directed tongues 76 at opposite sides of the slot 74 for interlocking engagement with correspondingly-shaped grooves 77 at the sides of the wedges. The tongue-and-groove connection of the wedges 68 and 69 with the member 75 serves to cause the wedges to be moved longitudinally with the member while permitting radial sliding movement of the wedges in the slot 74.

The actuating member 75 has a rearwardly-extending tubular flange 78 which is received in the forward end of a sleeve 79, to which it may be fixedly connected by brazing, welding or otherwise. The sleeve 79 extends through the axial bore 80 of the tubular spindle 7 with its rearward end projecting beyond the rearward end thereof. The rearwardly-projecting end of the sleeve 79 mounts a thrust-ring 82 having laterally-projecting pintles 83 at its opposite sides. The thrust-ring 82 is relatively free rotatively of the sleeve 79 and held axially thereof between anti-friction thrust-bearings 84 and 85. The thrust bearings 84 and 85 are held in adjusted position longitudinally of the sleeve 79 by means of split nuts 86 and 87 at opposite sides of the bearings. The nuts 86 and 87 may be adjusted axially of the sleeve 79 by turning them on screw-threads 81 on the sleeve to regulate the position of the thrust-ring 82 longitudinally thereof and then fixed in any adjusted position by tightening their binding screws 88.

The sleeve 79, actuating member 75, and wedges 68 and 69 are adapted to be moved

longitudinally of the spindle 7 by hydraulically-operated means comprising a lever 90 pivotally mounted intermediate its ends on a bracket 91 attached to a depending portion of the bearing-housing 2. The upper end of the lever 90 is forked to straddle the thrust-ring 82 and is provided with slots 92 at its ends in which the pintles 83 on the ring engage. Embracing the lever 90 between its pivot and forked end is a bifurcated bracket 93 attached to the depending portion of the bearing-housing 2 and having abutments 94 and 95 engageable by the lever to limit its rocking movement in opposite directions. The abutment 95 is of U-shape with its sides fixedly connected to the sides of the bracket 93 by screws 96; while the abutment 94 is in the form of a set-screw screwed through the end of the bracket and adapted to be locked in adjusted position by a check-nut 97. The lower end of the lever 90 is connected by a pin 100 to the end of the piston-rod 98 of a hydraulic motor 99 shown in sectional diagrammatic view in Fig. 6. The hydraulic motor 99 comprises a cylinder 101 enclosing a reciprocating piston 102 connected to the end of the piston-rod 98. The cylinder 101 of the hydraulic motor 99 has a projection at its end, see Fig. 1, positioned between the sides of a clevis 104 attached to a portion of the housing 2 which forms a casing for the flywheel 49 and connected to the clevis by a pin 103 to permit a slight rocking movement of the cylinder. The cylinder 101 has ports 105 and 106 arranged at opposite sides of the piston 102 for supplying motive fluid thereto and exhausting it therefrom.

The hydraulic circuit for controlling the flow of motive fluid to the cylinder 101 of the hydraulic motor 99 is illustrated diagrammatically in Fig. 6. The motive fluid is supplied from a tank 108 and continuously circulated by a pump 109 driven from a suitable electric motor 110. The motive fluid is delivered from the pump 109 through a conduit 111 to the inlet port 112 in the casing of a valve 113. Connected to the conduit 111 is a relief valve 114 which is operative at a predetermined pressure to exhaust the motive fluid through a conduit 115 to the tank 108. Mounted to rotate in the casing of the valve 113 is a valve-plug 116 which has recesses in the opposite sides of its periphery to provide passageways 117 and 118. The valve-plug 116 has a manually-operable treadle 119 connected at its end and the treadle normally is adapted to be rocked counterclockwise to the position shown by full lines in Fig. 6 by a spring 120. When the valve-plug 116 is in the position shown in Fig. 6 the passageway 117 connects the inlet port 112 with a port 121 in the casing of the valve 113. A conduit 122 connects the port 121 in the casing of the valve 113 with the port 105 in the cylinder 101 of the hydraulic motor 99 to deliver motive fluid to the lefthand side of the piston 102. A conduit 123 connects the port 106 in the cylinder 101 at the right-hand side of the piston 102 with a port 124 in the casing of the valve 113. The passageway 118 in the valve-plug 116 leads from the port 124 to an exhaust port 125 in the casing of the valve 113 and the motive fluid may be exhausted to the tank 108 through a conduit 126 leading back to the conduit 115 to debouch into the tank 108. When the treadle 119 is depressed to the position indicated by dash-lines in Fig. 6 the passageway 117 will connect the inlet port 112 to the port 124 in the casing of the valve 113.

to direct motive fluid delivered from the pump 109 to the right-hand side of the piston 102 in the cylinder 101 of the hydraulic motor 99. Simultaneously, the passageway 118 will connect the port 121 to the exhaust port 125 in the casing of the valve 113 to exhaust motive fluid from the left-hand side of the piston 102 in the cylinder housing 101. A preferred construction of machine incorporating the novel features of the present invention having been described in detail, the mode of operation of the complete apparatus is explained as follows.

Let it be assumed for the purpose of description that the flywheel 49 and spindle 7 are being rotated by the belts 53 and the dies 32 and 33 are being maintained in their open position as shown in Figs. 1 and 2 under the action of centrifugal force. As the spindle 7 rotates at a relatively high rate of speed the hammers 28 and 29 will be moved radially outward in the spaces between successive rollers 35 due to centrifugal force acting on the hammers and then will be forced radially inward by the engagement of their arcuate faces 30 and 31 with the rollers. The hammers 28 and 29 thus are reciprocated rapidly with a predetermined constant stroke as determined by the spacing of the rollers and the radius of the arcuate faces 30 and 31 of the hammers. The reciprocatory motion of the hammers is transmitted through the wedges 68 and 69 to the dies 32 and 33, it being noted that Fig. 1 shows the wedges as in their rearward or retracted position with the dies open to receive the work.

35 The cable C and fitting W, shown in the form of a bead, may be prepared for a swaging operation by applying the fitting in proper position on the end of the cable and temporarily attaching it thereto as by striking it with a hammer or by 40 any other suitable means. The cable C with the fitting W temporarily attached thereto is then placed in the axial bore 64 of the work-holding guide 60. For this purpose the sectional halves of the work-holding guide 60 may be separated 45 in the manner illustrated in Fig. 5 to adapt the guide to receive the cable and thereafter the halves are brought together to retain the cable therebetween. The work-holding guide 60 having the cable C inserted therein with the spherical fitting W attached thereto may be inserted 50 through the bushing 47 in the door 45 until its flange 62 seats against the face 63 on the bushing. The end of the cable C thus will be caused to engage the tongue 56 to properly position the fitting W in alignment with the semi-spherical recesses 54 in the dies 32 and 33. The dies 32 and 33, however, will not engage the fitting W due to their open or radially-spaced relationship.

60 The operator of the machine then may depress the treadle 119, see Fig. 6, against the action of the spring 120 to rotate the valve-plug 116. Turning of the valve-plug 116 in clockwise direction will position the passageway 117 to connect the ports 112 and 124 in the casing of the valve 113. Motive fluid from the pump 109 then will flow through the conduit 111 and inlet port 112 of the casing of the valve 113 and out through the port 124 and conduit 123 to the port 106 in the cylinder 101 of the hydraulic motor 99 to apply pressure at the right-hand side of the piston 102, as viewed in Fig. 6. The pressure of the motive fluid on the piston 102 will cause it to move toward the left and the piston-rod 98 connected to the lower end of the lever 90 will rock

the latter in clockwise direction as viewed in Figs. 1 and 6.

Rocking movement of the lever 90 will be transmitted through its forked end connected to the pins 83 on the thrust-ring 82 to slide the sleeve 79 inwardly or toward the right as viewed in Fig. 1. The operating member 75 at the opposite end of the sleeve 79 thus will be caused to slide the wedges 68 and 69 forwardly from the position shown in Fig. 1 toward that shown in Fig. 3. The forward movement of the wedges 68 and 69 between the inclined faces 72 of the hammers 28 and 29 and the outward faces of the dies 32 and 33 will cause the latter to be progressively advanced inwardly toward each other to closed position as they rotate and reciprocate around the work. As the dies 32 and 33 move inwardly toward each other to approach a closed position they engage with and progressively compress the spherical fitting W. Due to the semi-spherical form of the recesses 54 in the dies 32 and 33 they will confine the material of the fitting W while maintaining its spherical form and reducing it to a lesser diameter to cause it to tightly grip the cable C. It has been determined that the material of the fitting W will actually flow into the interstices between the strands of the cable C and take a tight grip thereon, practically as resistant to tension as the cable itself. During the swaging operation the hammers 28 and 29, the dies 32 and 33 and the wedges 68 and 69 rotate as a unit with the spindle 7.

During a swaging operation the hydraulic motor 99 will positively operate the lever 90, sleeve 79 and wedges 68 and 69 whereby the wedges will progressively close the dies 32 and 33 with a predetermined rate of motion corresponding to the amount of motive fluid delivered to the cylinder 101 of the hydraulic motor. The dies 32 and 33 will be closed progressively at a rate of motion as controlled by the hydraulic circuit commensurate with the proper rate of reduction of the work so that the machine will operate at maximum efficiency to apply the fitting W to the cable C. The closing movement of the dies 32 and 33 will be limited by the engagement of the lever 90 with the abutment 95 on the bracket 93 and the motive fluid being delivered from the pump 109 will thereafter escape through the relief valve 114 and exhaust to the tank 108.

At the completion of a swaging operation the treadle 119 will be released and operated by the spring 120 to move it from the position indicated by dash-lines to the position shown by full lines in Fig. 6. The inlet port 112 in the casing of the valve 113 then will be connected to the port 121 by the passageway 117 in the valve-plug 116 to direct motive fluid supplied from the pump 109 through the conduit 122 and port 105 in the cylinder 101 of the hydraulic motor 99 to the left-hand side of the piston 102. Simultaneously, the port 124 in the casing of the valve 113 will be connected to the exhaust port 125 by the passageway 118 in the valve-plug 116 to exhaust motive fluid from the right-hand side of the piston 102 through the conduits 123, 126 and 115 to the tank 108.

The piston 102 thus will be moved toward the right as viewed in Fig. 6 to rock the lever 90 in counterclockwise direction and retract the sleeve 79. The rearward end of the wedges 68 and 69 being interlocked with the operating member 75 also will be retracted and the rotating dies 32 and 33 will be moved outwardly away from each other by the action of centrifugal force to the

open position shown in Figs. 1 and 2. Opening movement of the dies 32 and 33 will release the swaged fitting W to permit it to be withdrawn. The opening movement of the dies 32 and 33 may be adjusted to the proper extent to adapt the work to be inserted therebetween by turning the set-screw 94, see Fig. 1, which limits the rocking movement of the lever 90. The machine may be continuously operated in the manner explained above by periodically inserting a cable C in the axial bore 64 in the work-holding guide 60, inserting the work-holding guide in the bushing 47 in the door 45 and depressing the treadle 117.

While the machine as illustrated in Figs. 1 to 5 is adapted particularly for applying spherical fittings W to cables C and for other similar work it is to be understood that by modifying the form of the dies 32 and 33 the machine may be fitted to apply annular fittings of different shapes to articles of other types. For example, Figs. 7 and 8 illustrate a form of die 130 and 131 for applying cylindrical bearing sleeves S to the reduced intermediate portion of forked rods such as used in the steering gears of automobiles. As shown in Fig. 7, the rod K comprises a straight portion M having an enlarged ball B at one end and a fork F at the opposite end. With such an article the bearing sleeve S must have an inside diameter greater than the outside diameter of the ball to adapt it to be slid onto the rod K. The sleeve S therefore will have a materially greater inside diameter than the outside diameter of the rod K and will require considerable reduction to cause it to seat thereon. If the sleeve S were to be swaged in the usual manner in a rotary swaging machine by moving it axially between the tapered recesses of cooperating dies, the relatively steep angle of the taper of the recesses would cause considerable difficulty in retaining the sleeve in its proper position on the rod during a swaging operation. The machine of the present invention, however, is particularly adapted for applying such sleeves S to the rod portions M of articles of the type last described as the dies will swage the sleeve radially inward without exerting any longitudinal component of force.

Each die 130 and 131 is provided with a semi-cylindrical recess 132 in its inner face having inclined sides 133 and a flaring recess 135 in its forward face. At the rear of the recess 132 each die may be provided with a clearance recess 136 for receiving the ball B. The die 131 also is provided with an abutment or tongue 137 for engaging the ball B and the die 130 has a slot 138 for receiving the tongue. Wedges 68 and 69 are provided between the dies 130, 131 and hammers 28, 29 for operation by the same hydraulic means as described above.

To prepare the work for swaging, the sleeve S may be slid over the ball B onto the straight portion M of the rod K and located in the approximate position of the recess 132 in the dies 130 and 131. Assuming that the spindle 7 is rotating, the operator will depress the treadle 119, see Fig. 6 to cause the piston 102 of the hydraulic motor 99 to move toward the left to rock the lever 90 clockwise and advance the sleeve 79 and wedges 68 and 69. The dies 130 and 131 thus will be advanced inwardly toward each other as they rotate around the work and rapidly reciprocated through a constant stroke. As the dies 130 and 131 are closed progressively the inclined sides 133 of the recesses 132 will engage the sides of the sleeve S to hold it in proper position between the dies. As the dies 130 and 131 continue to close

they will swage the sleeve to reduce it until it is seated fixedly on the rod K as shown in Fig. 8 and the recesses 132 will confine the material of the sleeve to form a finished bearing boss. Preferably, the shaft M of the article K is flattened, knurled, or otherwise formed to interlock with the sleeve as the latter is swaged in place thereon.

It will be observed from the foregoing specification that the present invention provides a rotary swaging machine in which the dies are simultaneously rotated and reciprocated and progressively advanced inwardly toward each other during a swaging operation. It also will be observed that the present invention provides hydraulic operating means for positively advancing the dies inwardly toward each other with a predetermined rate of movement to adapt the work to be progressively reduced in diameter. It will be observed still further that the present invention provides a machine which is of simple and compact construction and arrangement and one which is efficient in performing its intended function.

While a preferred construction of the machine and several different forms of work adapted for swaging therein are illustrated and described herein, it is to be understood that modifications may be made in the form and structure of the parts of the apparatus and that fittings of other forms and shape may be swaged in the machine without departing from the spirit or scope of the invention. Therefore, without limiting myself in this respect, I claim:

1. In a rotary swaging machine, a pair of dies mounted for reciprocatory motion and having cooperating recesses in their opposed faces for engaging the work, one of said dies also being provided with a projection in the form of a stop at a point adjacent its recess adapted to engage the end of the work to locate it relative to the point of application of the recesses thereto, means for rotating the dies, and means for reciprocating the dies to cause their cooperating recesses to swage the work.

2. A swaging machine for attaching annular fittings to articles of manufacture comprising a rotary head, a pair of dies reciprocable in said

head and formed with cooperating recesses in their opposed faces, one of said dies having a groove and the opposite die having a tongue adapted to enter the groove when the dies are moved toward each other, said tongue being adapted to engage the end of a rod or other part entered between the dies to locate the fitting opposite the recesses in the dies, means for rotating the head, and means for reciprocating the dies in the head to reduce the fitting to swage it on the rod or other part.

3. A swaging machine comprising a rotary head, dies reciprocable radially in said head, said dies having a plurality of cooperating circular recesses in their opposed faces shaped to conform to the work to be swaged, one of said dies also having a pair of grooves in its working face spaced apart and located inwardly between the recesses and said opposite die having tongues adapted to enter said grooves when the dies are closed together and acting as stops to locate a rod or other part with reference to the recesses in the dies, means for rotating the head, and means for reciprocating the dies to cause them to swage a fitting or other part at a point adjacent the end of a rod or other work inserted between the dies.
